UNITED STATES PATENT OFFICE.

FREDERICK AUGUSTUS JONES, OF WAGGA WAGGA, NEW SOUTH WALES, AUSTRALIA.

FAUCET ATTACHMENT.

1,142,579.

Specification of Letters Patent. Patented June 8, 1915.

Application filed August 27, 1914. Serial No. 853,925.

To all whom it may concern:

Be it known that I, FREDERICK AUGUSTUS JONES, a subject of the King of Great Britain and Ireland, &c., residing at Wagga Wagga, in the State of New South Wales, Commonwealth of Australia, have invented certain new and useful Improvements in Faucet Attachments; and I do hereby declare the following to be a full, clear, and exact description of the invention, such as will enable others skilled in the art to which it appertains to make and use the same:

This invention relates to attachments of the class which is applied to faucets, especially those for liquids to be used as food such as milk, the purpose of the attachments being to keep the taps quite clean. I am aware of and have myself in part invented other devices of the class above stated, but the present invention introduces improvements.

To keep dust off the nozzle of the faucet or tap I provide a box which is formed in two parts, its front part being a hollow casing which (so that it can be raised at will) is pivoted or mounted on a hinge which is suitably supported on the tap. This front casing is so connected to other parts that it will rise at the same time that the plug of the faucet is opened. A cam device is provided on the plug to operate on the casing for that purpose. This cam is preferably made of a removable wire but a slotted plate may be used instead. The open casing leaves the nozzle end free for the discharge of liquid. Gravity will suffice to close the casing, but it is better to assist gravity, and to hold the casing quite closed against the fixed back of the box, and therefore I provide any suitable spring closing device. On any suitable part above the outlet of the nozzle I provide means to support the aforesaid back of the box. Outside this back, as to its base, I attach means as arms to hold in place the faucet plug for ordinary use, but the arms are springy or adapted to be opened apart so as to allow of easy detachment of the plug to clean it and other parts of the faucet.

My invention will be understood by reference to the accompanying drawings which show one embodiment thereof.

Figure 1 is a partly sectional side elevation of a faucet having a nozzle which is shown closed. Fig. 2 is a partly sectional elevation showing the parts in Fig. 1 with

the hollow front of the box raised. Figs. 3 and 4 each shows a plan of a faucet with the said front of the box in closed, and in nearly fully open, position respectively; Fig. 5 shows a plan from below of the parts as they are located in Fig. 4. In the latter figure the plug is shown partly in section.

1 indicates a shank of a tap or faucet having a nozzle 2 with discharge end 2^a, and a plug of suitable kind, as 4 with handle 4^a. The plug foot, 5, is of reduced diameter with its end screw-threaded to carry a nut 6 to press a washer 6^a against two jaws or arms 9 which grip between them part of foot 5. 60 These side arms 9 have a suitable support as 9^a on a member 3 at the back of the nozzle box. A screw-thread 8^a is provided on the nozzle 2, back of which is a flange or shoulder 8. Over the nozzle is slipped the back plate 3, in front of which is placed a rubber or like gasket 3^a to form a seating for the edges of the movable part 7 of the nozzle box to close against to exclude dust and foreign matter. A binding plate 3^b is placed 65 in front of the gasket and pressed firmly against it as by a nut 10. The back of the nozzle box is also thus made a fixture which will remain immovable during ordinary openings and closings of the box member 7. 70 But the gasket can be removed and a new one substituted at will.

A suitable spring 12^a and a hinge pin 12 are provided, the spring being shown as in part a spiral one around the said pin, its ends being so arranged that it will normally press the box member 7, which works on the said pin, down to its closed position. The upper rear part of member 7 has a projection 11, which may be a horn or an eye, 75 and which is so engaged by a cam device that it can be pressed by a cam to lift member 7. The cam device has two sides with similarly acting cams 13 and 14 which begin at a point 15, so that in whichever direction the plug handle 4^a is rotated from the position of Fig. 1, one cam or the other will press on horn 11 and thus gradually raise the member 7 more and more until the plug has fully opened the tap. The 80 back of each cam is connected by any suitable member, or an inwardly extending continuation of the same wire as that forming the cams, to a suitably located point 17 of the plug, where the wire or material 85 is secured as by entering its end in a hole 18, (see Fig. 4), in which these ends are

fixed in any suitable manner, as by a set screw 19. Or instead of using a hole 18 there may be a distinct device for fixing to the plug each wire end or cam holding 5 connection.

At 16 the material of the cams is shown at each side as having a kink or curve to allow ample room to turn the plug on full and yet allow the points of connection 17 10 with the plug to be located nearer to casing 7 than would otherwise be the case. Connections to the plug middle are illustrated, and these leave all the back part of the 15 plug, and plug casing, free of projections which might harbor dirt and be in the way of the fingers of a person manipulating the plug.

Though the nozzle box can be used without employing the plug grippers 9 the latter are preferably made part of the whole device as they promote a quick grip of the plug when the latter is returned after removal, the grippers then springing into place. An earlier form of two-door tap 25 protector has a slotted top plate having an under surface which in practice becomes dirty and is troublesome to clean. The said form also involves considerable weight and cost, and there is a liability for its two 30 doors to cease to close dust tight, the least opening admitting dirt direct to the nozzle exit. I therefore devised the present nozzle box back wall located at the rear of the nozzle exit, so that if dust did lodge there 35 it would probably not enter the milk or like fluid; I devised also this one-door tap protector; and did away with surfaces so placed that they would harbor dirt or be hard to clean. These improvements result 40 in a lighter, cheaper and more practical article which can be made if desired by alteration of existing faucets.

Having described this invention, what is claimed by Letters Patent is:—

45 1. The combination with a faucet provided with a valve plug and a nozzle, of a plate carried by said nozzle clear of its orifice and between said orifice and said plug, a box member hinged to said plate and adapted to form therewith a closed vessel inclosing the open end of said nozzle, and means operated by the turning of said plug for swinging said box member from the position in which it incloses said end of 50 the nozzle, substantially as described.

2. The combination with a faucet provided with a valve plug and a nozzle, of a plate carried by said nozzle clear of its orifice and between said orifice and said 55 plug, a box member hinged to said plate and adapted to form therewith a closed vessel inclosing the open end of said nozzle, a spring adapted to normally hold said box member in the position for inclosing said end of the nozzle, and means operated

by the turning of said plug to move said box member from said position against the action of said spring, substantially as described.

3. The combination with a faucet provided with a valve plug and a nozzle, of a plate carried by said nozzle clear of its orifice and between said orifice and said plug, a gasket carried by said plate, a box member hinged to said plate and adapted to engage 75 said gasket and to form therewith a closed vessel inclosing the open end of said nozzle, and means operated by the turning of said plug for swinging said box member from the position in which it incloses said end of 80 the nozzle, substantially as described.

4. The combination with a faucet provided with a valve plug and a nozzle, of a plate carried by said nozzle clear of its orifice and between said orifice and said plug, 85 a gasket carried by said plate, a box member hinged to said plate and adapted to engage said gasket and to form therewith a closed vessel inclosing the open end of said nozzle, a spring adapted to normally hold 90 said box member in the position for inclosing said end of the nozzle, and means operated by the turning of said plug to move said box member from said position against the action of said spring, substantially as de- 95 scribed.

5. The combination with a faucet provided with a valve plug and a nozzle, of a plate carried by said nozzle clear of its orifice and between said orifice and said plug, 100 a gasket carried by said plate, a box member hinged to said plate and adapted to engage said gasket and to form therewith a closed vessel inclosing the open end of said nozzle, and a cam arrangement operated by 105 the turning of said plug for swinging said box member from the position in which it incloses said end of the nozzle, substantially as described.

6. The combination with a faucet provided with a valve plug and a nozzle, of a plate carried by said nozzle clear of its orifice and between said orifice and said plug, a gasket carried by said plate, a box member hinged to said plate and adapted to engage 110 said gasket and to form therewith a closed vessel inclosing the open end of said nozzle, a spring adapted to normally hold said box member in the position for inclosing said end of the nozzle, and a cam arrangement 115 operated by the turning of said plug to move said box member from said position against the action of said spring, substantially as described.

7. The combination with a faucet provided with a valve plug and a nozzle, of a plate detachably mounted on said nozzle clear to its orifice and between said orifice and said plug, a resilient clip attached to said plate and adapted to engage the lower 120

end of said plug, whereby to aline said plate in the proper position, means for clamping said plate in place on said nozzle, a box member hinged to said plate and adapted to form therewith a closed vessel inclosing the open end of said nozzle, and means operated by the turning of said plug for swinging said box member from the position in which it incloses said end of the nozzle, substantially as described.

8. The combination with a faucet provided with a valve plug and a nozzle, of a plate detachably mounted on said nozzle clear of its orifice and between said orifice and said plug, a resilient clip attached to said plate and adapted to engage the lower end of said plug, whereby to aline said plate

in the proper position, means for clamping said plate in place on said nozzle, a box member hinged to said plate and adapted to form therewith a closed vessel inclosing the open end of said nozzle, a spring adapted to normally hold said box member in the position for inclosing said end of the nozzle, and means operated by the turning of said plug to move said box member from said position against the action of said spring, substantially as described.

In witness whereof I have hereunto set my hand in the presence of two witnesses.

FREDERICK AUGUSTUS JONES.
